UNITED STATES PATENT OFFICE.

JOHN L. POPE, OF CLEVELAND, OHIO.

DESIGN FOR A HARNESS-BIT.

SPECIFICATION forming part of Design No. 13,555, dated January 30, 1883.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Harness-Bits, of which the following is a specification, reference being had to the accompanying photograph, forming a part thereof.

My invention relates to a novel design for harness-bits, having reference particularly to the cheek-pieces thereof; and it consists in various features of contour and ornamentation.

In the two photographic views which accompany this specification, Figure 1 represents what is called a "half-cheek" bit, and Fig. 2 what is known as a "full-cheek" bit.

Similar letters indicate similar parts in the two views.

A is the bit proper, which in this case is shown to be of that kind known as a "snaffle-bit." B B are the loops or rings, and C C are the cheek-pieces. The cheeks and loops are shown as turned out of their regular positions to better show the design, their positions when in use being at right angles to those shown. The loops join the cheek-pieces at their solid neck portions, close to the bit. The design of each cheek-piece is about as follows: From the neck portion extend outwardly two branches, a a, that curve inwardly at b b, from which points to the extremity of the figure the general outline is that of a partial ellipse, two sides of which I designate by the letters c c. This con-

tour of the cheek-piece I render still more beautiful in appearance by the shown interior ornamentation, which I shall now briefly describe. Between the points b b a loop or oval figure is formed, which joins an arch-shaped piece, whose ends merge into the sides c c of the partial ellipse. Between this arch-shaped or semicircular piece and the other end of the partial ellipse is produced a triangularly-formed figure, n, made of crooked bars, whose ends extend beyond the three-cornered figure and run into the arch and into portions of the partial ellipse, as is apparent from an inspection of the photographs.

My invention may be used in any kind of harness-bit:

What I therefore claim as new, and desire to secure by Design Letters Patent, is—

1. A harness-bit with cheek-pieces designed substantially as shown.
2. A harness-bit with cheek-pieces embodying substantially the contour shown and described.
3. A harness-bit cheek-piece with interior ornamentation, substantially as described and shown.

In witness whereof I have hereunto set my hand this 3d day of November, 1882.

JOHN L. POPE.

In presence of—

WALTER A. BIDDLE,
GEORE F. EBERHARD.
